(57) **CLAIM**

I claim the ornamental design for shooting duck game, as shown and described.

DESCRIPTION

FIG. 1 is a front perspective view of a shooting duck game. FIG. 2 is an alternate front perspective view of a shooting duck game.

FIG. 3 is a front view of the shooting duck game of FIG. 1. FIG. 4 is a rear view of the shooting duck game of FIG. 1. FIG. 5 is a side view of the right side of the shooting duck game of FIG. 1.

FIG. 6 is a side view of the left side of the shooting duck game of FIG. 1.

FIG. 7 is a top view of the shooting duck game of FIG. 1; and,

FIG. 8 is a bottom view of the shooting duck game of FIG. 1.

The dashed lines in various figures are for illustrative purposes only and form no part of the claimed design.
